ELECTROMAGNET.

1,134,779.

Specification of Letters Patent.

Patented Apr. 6, 1915.

Application filed August 5, 1913. Serial No. 783,136.

To all whom it may concern:

Be it known that I, ARTHUR R. TREZISE, Sr., a citizen of the United States, residing in Brooklyn, in the county of Kings and 5 State of New York, have invented a new and useful Improvement in Electromagnets, of which the following is a specification.

My invention relates to electromagnets having one or more cores of the plunger 10 type, and relates more particularly to an improved bushing for guiding the cores, and comprises a tube composed of Scotch glass, which is well known for its specific hardness, which feature makes the adaptation 15 thereof for the purpose herein set forth, very desirable.

In electromagnets having a vertically movable core of the plunger type, it has long been observed that the tube portion of the 20 magnet spool in which the core is adapted to move, and which generally is made of brass or fiber, offers a considerable amount of resistance to the movements of the core, due to the fact that the mechanical center 25 of the spool does not coincide with the magnetic center of the coil, thus when the magnet coil is energized it causes a side pull on the core, which causes the latter to rub against the side of the tube. This continued 30 rubbing soon wears grooves in the tube which greatly increase the resistance to the movements of the core, and either renders its action extremely sluggish or prevents its movement altogether. This defect in the 35 magnet necessitates the replacement thereof by a new magnet spool and coil, which is an expensive article of manufacture, and in an installation such as an electric elevator 40 installation for example, wherein the electric brake and various switches of the controlling system have cores of the plunger type, cause a great amount of delay in making a replacement.

In electromagnets having two cores movable longitudinally, the grooves are caused by the weight of said cores, which causes the same to continually rub against the inner surface of the spool, and in order to overcome these objectionable features, I purpose to use a cheap and durable means 45 capable of insertion in the magnet spool, said means comprising a tube made of Scotch glass, which is well known for its specific hardness, and for its adaptability to withstand variable heat temperatures,

which are common to direct current magnets and more particularly alternating current magnets.

In the accompanying drawings, Figure 1, shows the application of my invention to an 60 electromagnet having a single core movable vertically therein; Fig. 2 shows the application of my invention to an electromagnet having two cores movable longitudinally therein; Fig. 3 is a fragmentary section of a 65 glass tube.

In detail the mechanism shown in the drawings comprises a magnet winding 1, contained in a magnet frame 2, which may be of any well known construction. A brass 70 tube 3, provided with flanges supports a spool 4 made of fibroid or other suitable insulating material. A tube 5, made of Scotch glass fits the interior of the brass tube 3, to guide the core 6, and is held securely 75 therein by a nut 9. Rubber washers 8 are interposed at both ends of the tube 5 to protect same against mutilation. In an electromagnet of the type shown in Fig. 2, I provide nuts 9 to secure the tube 5 in 80 position.

The advantages obtained by the adaptation of a tube composed of glass to an electromagnet as herein shown are as follows: It gives a very desirable protection against 85 the wearing of grooves by the movement of the core or cores therein; owing to its specific hardness, it offers practically no resistance to the movements of the core, and it affords a perfect insulation for the magnet coil due to the high electric resistance 90 qualities.

I purpose to adapt my invention to any of the well known types of electromagnets now in common use, having a core or plurality of cores of the plunger type, and therefore wish not to be limited in its application to electromagnets of the particular construction herein shown.

What I claim and desire to protect by 100 Letters Patent of the United States is:—

1. In combination, an electromagnet comprising a movable core in plunger form, a member composed of glass adapted to guide the core, and elastic members located at 105 either end of the glass member.

2. In combination, an electromagnet comprising a magnet coil and spool therefor, a movable core in plunger form, a glass tube positioned inside of the spool to guide the 110

2. core, elastic members located at each end of the glass tube, and means for exerting a pressure on said members to retain the glass tube in position.
3. An electromagnet comprising a magnet coil and spool therefor, a movable core in plunger form, a member composed of Scotch glass positioned in the hollow portion of the spool, the glass member formed to permit a free movement of the core therein, and elastic members located at each end of the glass tube.
4. An electromagnet comprising a magnet coil and spool therefor, a movable core in

plunger form, a member composed of Scotch 15 glass capable of insertion inside of the spool, said member formed to permit a free movement of the core therein, elastic members positioned on both ends of the glass member, and means to retain the latter in its 20 proper position relative to the core.

In testimony whereof, I have signed my name to this specification in the presence of two subscribing witnesses.

ARTHUR R. TREZISE, Sr.
